UNITED STATES PATENT OFFICE.

CHARLES WHITING BAKER, OF MONTCLAIR, NEW JERSEY.

ROADWAY.

SPECIFICATION forming part of Letters Patent No. 781,988, dated February 7, 1905.

Application filed February 17, 1904. Serial No. 194,063.

To all whom it may concern:

Be it known that I, CHARLES WHITING BAKER, a citizen of the United States, residing at Montclair, in the county of Essex and 5 State of New Jersey, have invented certain new and useful Improvements in Roadways, of which the following is a specification.

My invention consists of a permanent way adapted for the use of the cars or cars and locomotives described in my application, Serial 10 No. 181,682, filed November 18, 1903, said cars and locomotives having wheels at their center adapted to run upon a rail and arranged to carry the principal weight of the vehicle 15 and said vehicle being kept balanced upon said central wheels by auxiliary wheels at the sides adapted to run upon flat bearings or the ground and which may be similar to ordinary vehicle-wheels. In said locomotive system 20 also the traction is secured by horizontal driving-wheels gripping the sides of the rail-head.

In the drawings, Figure 1 is a plan of a roadway embodying my improvement. Fig. 2 is a cross-section. Fig. 3 is an enlarged cross-25 section of the rail used, showing also the form of rail-joint employed; Fig. 4, a side elevation of Fig. 3. Fig. 5 is an enlarged plan of a turnout. Fig. 6 is an enlarged plan of the portable frog used at turnouts. Fig. 7 is an 30 elevation of the frog shown in Fig. 6.

As shown in Figs. 1 and 2, the permanent way consists of a single rail R laid in the center of the road-bed and suitably supported on a longitudinal stringer S or by other suitable 35 means, together with paved paths p p in the road-bed, one at each side of and equidistant from the central rail R, said paths being adapted to constitute bearings for the balancing-wheels of the vehicles. These paths may be 40 paved with a variety of materials, according to local circumstances; but ordinarily they will consist of a narrow strip of macadam or telford construction so laid that its finished surface will be even with the general surface 45 of the road-bed. The surface between the central rail and the paved strips I prefer to have slightly sloping each way from the center to secure drainage, and in order to prevent dust and wash I prefer to cover it either with 50 a growth of grass, as indicated at a, Fig. 2,

or a coating of gravel or broken stone, as shown at b. Where it is desired to have the road-bed used by ordinary vehicles as well as those running on the central rail, all or part of the remainder of the road-bed between or 55 outside of the paved strips p p may be also paved or surfaced in any desired manner.

As the traction in my system is preferably produced through gripping the sides of the rail by horizontal driving-wheels, it becomes 60 important to make the rail-head with vertical sides of considerable width to give ample bearing area for the gripping driving-wheels. I therefore prefer to depart from the usual standard form of T-rail section and to use a rail 65 having deep side faces, as with a head nearly square in cross-section. The height of the rail may also be reduced from the usual standard, since the rail is continuously supported on the longitudinal stringer S and not necessarily 70 on the cross-ties in the usual manner.

As the traction of the driving-wheels upon the rail tends to slide it longitudinally or cause creeping, I attach each rail firmly to the supporting-stringer S by any suitable means, as 75 by screw-bolts c c, at some point in its length, so as to prevent such longitudinal movement, and to prevent the stringer itself from being moved endwise I provide it with wings m, secured thereto and buried in the ground. 80 For instance, I spike projecting cross-pieces to the sides or bottom of the stringer, as shown.

As the treads of the driving-wheels preferably roll against the sides of the rail-head and their flanges project below, as shown in dotted lines, it is not practicable to use the ordinary fish-joint of the angle-bar type. In its place I use a rail-joint which is mainly below the rail and clamps the foot or base of the rail 85 only. As shown in Figs. 3 and 4, the joint is arranged in a recess w of the stringer and consists of a pair of plates d d with the hook-flanges h h at the top, formed to fit the foot flanges of the rail, and plain flanges f f at the 90 bottom, which afford a bearing on the face of the stringer. A single bolt e at the center draws these two plates together. The stringer S has preferably an inclined face y where it 95 is cut out, so that a wedge W, driven beneath 100

the feet of the joint-plates, serves as a bearing and means of adjustment. Thus the joint gives support to the rail ends besides acting as a splice.

- 5 The turnouts in my roadway system are in general similar in principle to the stub-switch in use on ordinary railways. There is a moving rail V, Fig. 5, which is shifted to either side to aline with either the main-line rail K or the rail T, leading to the siding. The throw of the switch, however, is necessarily made great enough so that the horizontal driving-wheels can pass through the switch without striking the opposite rail. To enable the balancing-wheels to cross the rail, I may either leave an opening *w* at the point where the wheels will cross it or use a portable frog or bridge—such, for instance, as shown in Figs. 6 and 7—with inclines *j j* and recesses *g* to receive the rails, whereby the wheels are led on the inclines up and over the rails and down on the opposite side. It will be evident that this frog can be placed on either rail of the turnout to suit the position of the switch.
- 15 25 While I have referred to my improved roadway, especially in connection with a construction in which the cars are driven by motors and provided with drive-wheels, it will be evident that it is applicable to other modes of propulsion—as, for instance, when the cars are drawn by animals or by a traveling cable.
- Without limiting myself to the precise construction and arrangement of parts shown, I claim—
- 30 35 1. A permanent roadway comprising a road-bed having parallel paved bearing-strips form-

ing paths in the road, and a central rail, substantially as described.

2. In a railway adapted for the use of locomotives having horizontal driving-wheels gripping a central rail, the combination with a rail, of a supporting-stringer having a recess, a rail-joint consisting of clamping-plates for clamping the foot of the rail and a bolt for drawing the plates together, the clamping-plates being located in the recess in the stringer and supporting and engaging the foot of the rail, substantially as described.

3. In a railway adapted for the use of locomotives having horizontal driving-wheels gripping a central rail, the combination with a rail, of a supporting-stringer having a recess with an inclined base, a rail-joint clamping the foot of the rail and located in said recess, and a wedge interposed between the rail-joint and inclined base of the stringer, substantially as described.

4. In a single-rail railway system adapted to vehicles having central wheels and balancing-wheels; a turnout consisting of a movable rail, stationary switch-rail and main rails, and a portable incline for passing the balancing-wheels over either rail, substantially as described.

In testimony whereof I have signed my name to this specification in the presence of two subscribing witnesses.

CHARLES WHITING BAKER.
